COMBINATION GARMENT AND BLANKET

Verne L. Stephenson, Goshen, Ind.

Application April 15, 1953, Serial No. 348,855

4 Claims. (Cl. 2—69)

This invention relates to a combination garment and blanket, and more particularly to a blanket which is adapted for use as a cover or for any other use to which a blanket is normally adapted, and which is provided with separable fasteners accommodating the formation of a garment from the blanket.

In particular this invention relates to improvements upon my co-pending United States patent application, Serial No. 205,979, filed January 15, 1951, now Patent No. 2,656,540.

The primary object of this invention is to provide a combination blanket and garment with a novel arrangement of fasteners which facilitates the use of parts of the same fastener either for securing the blanket in garment-forming position or for holding the garment in compactly folded form for convenient storage, handling and carrying.

Other objects will be apparent from the following specification.

In the drawings:

Fig. 1 is a plan view of the blanket laid flat and illustrating in dotted lines the lines along which the blanket is folded;

Fig. 2 is a perspective view of the blanket in partially folded condition with parts broken away to show the manner in which the blanket is folded for use as a garment;

Fig. 3 is a perspective view illustrating the blanket in fully folded condition but with one fastener thereof open;

Fig. 4 is a perspective view illustrating the blanket in fully folded form with the fasteners completely applied.

Referring to the drawings, the numeral 10 designates a blanket which is preferably of rectangular shape and which preferably has fringe 12 extending from its opposite ends. The blankets may be of any size found suitable and will preferably be of the character which is used by sportsmen for cuttings, by motorists as a lap robe, by sporting enthusiasts when attending athletic contests, such as football games, in cold weather, and by athletes.

The complementary parts of an elongated slide fastener of conventional construction are secured to opposite longitudinal margins of the blanket. The fasteners will preferably be of the well known type having a cloth strip 14 to which teeth 16 are secured. The strips 14 will be sewed or otherwise secured to the blanket at the same face thereof and will preferably be of the same length, and will be similarly positioned upon the blanket with respect to the spacing thereof from opposite ends of the blanket. Thus, as shown in Fig. 1, each of the fasteners will be of a shorter length than the blanket and will terminate spaced therefrom at each end. The arrangement will be such that, when the blanket is folded to bring the opposite longitudinal edges thereof adjacent to each other, the teeth will be placed in mating position so that the slider member 18 carried by one of the sections may engage the starting end portion 20 of the other sec-

2

tion, and thereupon the slider 18 may slide lengthwise of the two sections to cause the teeth 16 to interlock. It will be understood that, while one elongated fastener is shown herein, two or more fasteners may be employed instead, thus making it possible for a selected fastener only to be secured, or for all fasteners to be secured.

A pair of sets of fasteners of the same separable slide type are mounted in longitudinal alignment to extend transversely of the blanket adjacent one end of the longitudinal slide fasteners. Each of these slide fasteners will be of the same type discussed previously, having a tape portion 22 carrying projecting teeth 24, with one unit of each set or pair carrying a slider 26, and the other unit of each pair having a starting part 28. The parts 30 and 32 constitute one set or pair, and the parts 34 and 36 constitute another set or pair. The parts of each set are located adjacent to each other in end to end alignment, as shown. The outermost or starting end of the unit 30 is located adjacent to one end of the tape 14 of one section of the longitudinal fastener, and the starting end 28 of the unit 36 is located adjacent to the end of the other tape 14 on the other longitudinal fastener.

Each of the units 30, 32, 34, 36 is of a length slightly less than one-quarter of the transverse dimension of the blanket 10 so that the total length of the four fastener sections 30, 32, 34, 36 is not equal to the width of the blanket and interruptions occur between these sections or parts. For this purpose the parts 32 and 34 will be arranged with their innermost ends adjacent to the longitudinal center line of the blanket, as indicated by the dotted line 38, and will extend from that center line and a relation of substantial end abutment in the direction of the units 30 and 36, respectively. The part 32 will preferably be arranged with its starter 28 located adjacent to the center line 38, and the part 34 will preferably be arranged with its slider 26 having a starting position adjacent to the center line 38. There is a spacing between the parts 30 and 32 of one set substantially equispaced from the longitudinal fold line 40, and a similar spacing of the adjacent ends of the complementary fastener parts 34 and 36 from the longitudinal fold line 42. Each of the fastener parts 30, 32, 34, 36 will be secured to the same face of the blanket at which the strips 14 of the longitudinal fasteners are secured. Also, as will be seen in Fig. 1, the fastener parts 30, 32, 34, 36 will be so arranged that the teeth 24 thereof are located at the side thereof nearest adjacent fringed end of the blanket. This construction is substantially the same as the construction shown in my co-pending application, Serial No. 205,979.

In spaced relation to the opposite end of the blanket and adjacent to the opposite ends of the longitudinal fastener are provided one or more transverse fastener sections. I prefer to employ two such fastener sections 44 and 46, as shown in Fig. 1, although either may be omitted if desired. The section 44, where used, will be complementary to the section 32 of the fastener 30, 32, that is, will be of substantially the same length and will be constructed to mate with the fastener unit 30. The unit 44 will extend transversely of the robe from a point adjacent the longitudinal edge thereof and also adjacent to the tape 14 of one longitudinal fastener section, and will terminate at its inner end spaced from the longitudinal fold line 40. The starter part 48 of the fastener 44 will be located adjacent the marginal edge of the robe. If a second fastener element 46 is employed, it will be positioned similarly to the part 44 to extend inwardly and transversely from a side edge of the blanket opposite that at which the part 44 is secured and adjacent to the end of the longitudinal fastener tape. The fastener part 46 will be complementary to the section 36 of the fastener 34, 36 and will have a slider 50 adapted to start interengage-

ment with part 36 adjacent the longitudinal edge of the blanket. The fasteners 44, 46 are so arranged that their teeth 45 and 47 are positioned outwardly and adjacent to the fringed end of the blanket. Sections 44 and 46 are secured to the blanket at the same face thereof at which the other fasteners above described are secured.

The blanket is adapted to have, in addition to the longitudinal fold lines 38, 40, 42 above described, a substantially intermediate transverse fold line 52, an end transverse fold line 54 substantially aligned with the fastener sections 30-36, and an opposite transverse end fold line 56 substantially aligned with the fastener or fasteners 44, 46.

The blanket may be used as a covering without substantial interference from the fasteners by reason of the fact that all of the fasteners are secured at the same surface thereof. When used as a covering, the surface carrying the fasteners will preferably be uppermost. However, the fasteners will not interfere with the reverse positioning of the robe as a cover, that is, with the fasteners lowermost, although in this instance, especially if fasteners of the so-called uncovered type are used wherein the fastener teeth project beyond their fabric mounting strips, the material of the teeth may touch the body of the user. In cases where the fasteners are of the so-called closed type, wherein the teeth are anchored to the fabric or ribbon intermediate the width of the ribbon so that longitudinal margins of the ribbon lap the teeth, the ribbon will protect the user against direct contact with the teeth of the fastener.

The blanket may be formed as a garment in either of several forms. In one form where the blanket is folded at the longitudinal fold lines 40 and 42 so as to bring the mating fastener sections 30 and 32 together, and sections 34 and 36 together, a garment in the nature of a cape will be formed. In folding the blanket to form a cape, the end portion 58 located outwardly of line 54 will be folded on line 54, and then the folds at each of the fold lines 40, 42 will preferably be made in directions to position the marginal end portion 58 of the blanket innermost, as illustrated in Fig. 2. If it is desired to use the blanket portion 58 as a head covering, the cape may be inverted to position portion 58 outermost. This cape effect requires that the longitudinal fasteners shall be either wholly or partly open so as to permit the garment to fit over the shoulders of the user, with the end panels draping at the front of the user's body.

The blanket may be formed into a bag for protecting the feet and legs of a spectator at an outdoor game, such as a football game, by fastening the transverse fasteners 30, 32, 34, 36, and also the longitudinal fasteners 14, 16 to produce a unit substantially as illustrated in Fig. 2. A variant of this arrangement will include the partial fastening only of the transverse fasteners, thus leaving holes at the bottom of the blanket bag through which the user may extend his feet. In such instances the device may be used as a lap and leg protection by the driver of an automobile while affording to him free use of his feet to operate the control pedals of an automobile, such as the accelerator, the brake pedal and the clutch pedal.

The foregoing adaptations and uses of the device have all been described in my co-pending application, and this application is particularly concerned with the utility of the fastener strips 44 and 46. These are utilized, as best seen in Fig. 3, by folding the blanket upon the longitudinal fold lines 40 and 42 and upon the transverse fold lines 54 and 56 to substantially the position shown in Fig. 2 with the longitudinal fastener 14, 15 and one of the transverse fasteners secured. Thereupon, the blanket is folded upon the longitudinal center line 38 and thence upon the transverse center line 52 to position the parts in the condition shown in Fig. 3. The arrangement is such that one of the transverse fastener sets 30, 32, 34, 36 will be closed, and the other will be open. The open set will be positioned outermost as shown in Fig. 3. As-

suming that the open set is the set 30, 32, the fastener 30 will be positioned outermost, and the strip fastener 44 will also be positioned outermost. These parts may then be brought together and joined by the slider 26 so that the construction illustrated in Fig. 4 is produced. If the blanket is folded to position the fastener set 34, 36 outermost, the strips 36 and 46 at opposite ends of the blanket will be interlocked by the use of the slider 50 upon the strip 46. In both arrangements the blanket is held securely in its folded form and constitutes somewhat of a loop. This renders the blanket convenient for carrying purposes since the arm of the user may extend through the loop and hold the blanket in that fashion, that is, to be used and carried in a manner comparable to a woman's muff. Observe in this connection that this result is achieved by the use of only a single fastener at the end of the blanket opposite that at which the fasteners 30, 32 and 34, 36 are secured. It will be apparent that if only one unit, such as the unit 44, is provided, at this end of the blanket, then the blanket must always be folded to position the fastener 44 at the outermost fold of the blanket as it is folded to the Fig. 3 form. Where two such strips 44 and 46 are provided, however, the manner in which the blanket is folded is immaterial, since one or the other of the two parts 44, 46 will always be outermost at the end of the blanket which is to be joined to one of the opposite fastener units 30, 32 or 34, 36.

While reference has been made herein to the fact that the slider 26 of the fastener section 30 and the starter 28 of the section 36 are located outermost, and certain advantages result from this arrangement, that it, the possibility of providing leg openings in a blanket bag used to encase the legs, nevertheless, such an arrangement is not essential. In other words, it is possible to reverse the position of the starting end of each of the fasteners 30, 32, 34, 36. If this is done, then the starter 48 of the section 44 must be oriented similarly to the starting end of the strip 30, and the slider 50 of the strip 46 must be oriented similarly to the starter 28 of the strip 36.

It will also be understood that the longitudinal fasteners may be omitted and the advantages of the device partly retained, insofar as holding the unit in compact folded condition and accommodating formation of a cape are concerned.

While the preferred embodiment of the invention has been illustrated and described, it will be understood that changes in the construction may be made within the scope of the appended claims without departing from the spirit of the invention.

I claim:

1. An article of manufacture comprising a blanket having opposite longitudinal margins, two pairs of complementary slide fastener sections secured to said blanket to extend end to end in transversely aligned relation adjacent to one end of said blanket, said pairs being located on opposite sides of a longitudinal center fold and the sections of each pair being located on opposite sides of respectively adjacent longitudinal quarter-fold lines whereby said blanket may be folded transversely adjacent to said pairs of fastener sections and thence may be folded longitudinally along said quarter-fold lines to locate said transverse fastener sections of said pairs for interlocking engagement, and a slide fastener section secured to said blanket adjacent the opposite end thereof to extend transversely of the blanket and in register with one of said first named fastener sections to cooperate and interlock therewith when said blanket is folded along an intervening transverse fold line to juxtapose the same to said registering first named fastener section.

2. An article of manufacture as defined in claim 1, wherein all fasteners are secured to one surface of said blanket.

3. An article of manufacture as defined in claim 1, wherein all fasteners are secured to the same face of said blanket and in spaced relation to the ends of said blanket.

4. An article of manufacture comprising a blanket having opposite longitudinal margins, a pair of complementary slide fastener sections secured to said longitudinal margins and each having an end portion terminating spaced from one end of said blanket, said fastener sections being positioned to interlock when said blanket is folded along longitudinal quarter-fold lines, two pairs of complementary slide fastener sections secured to said blanket to extend end to end in transversely aligned relation adjacent to said last named end portions of said first named fastener sections and spaced from the end of said blanket, said pairs being located on opposite sides of a longitudinal center fold line and the sections of each pair being located at opposite sides of respectively adjacent longitudinal quarter-fold lines whereby said blanket may be folded transversely adjacent to said last named

10

15

fastener sections and thence may be folded longitudinally along said quarter-fold lines to locate said transverse fastener sections of said pairs for interlocking engagement, and a slide fastener section secured to said blanket adjacent the opposite end thereof to extend transversely of the blanket and in register with one of said first named transverse fastener sections to cooperate and interlock therewith when said blanket is folded along an interlocking transverse fold line to juxtapose the same with said registering first named transverse fastener section.
